G. J. SWEETSER,
AIR BRAKE HANDLE OR CONTROLLER HANDLE.
APPLICATION FILED APR. 26, 1916.

Patented Aug. 8, 1916.

UNITED STATES PATENT OFFICE.

GEORGE J SWEETSER, OF SAN FRANCISCO, CALIFORNIA.

AIR-BRAKE HANDLE OR CONTROLLER-HANDLE.

1,194,094.

Specification of Letters Patent.

Patented Aug. 8, 1916.

Application filed April 26, 1916. Serial No. 93,656.

To all whom it may concern:

Be it known that I, GEORGE J. SWEETSER, a citizen of the United States, residing at San Francisco, in the county of San Francisco and State of California, have invented certain new and useful Improvements in Air-Brake Handles or Controller-Handles; and I do hereby declare the following to be a full, clear, and exact description of the invention, such as will enable others skilled in the art to which it appertains to make and use the same.

This invention relates to new and useful improvements in an air brake handle or controller handle for electric cars and one of its objects is the provision of a device of this character, which shall be simple, durable and efficient, and which may be manufactured and sold at a comparatively low cost.

Another object of this invention is to provide a cylindrical barrel at one end of a handle, for receiving the valve stem or controller stem, having means therein for locking the stem within the barrel.

A further object of this invention is to provide a releasing lever operatively connected with the locking means for unlocking the barrel upon the stem when desired.

A still further object of this invention is to provide wedge shaped chuck within the barrel and operatively connected to the releasing lever for automatically locking the barrel to the stem, when said barrel is placed upon the valve stem or controlling stem.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a side elevation partly in section of an air brake handle or controller handle, constructed in accordance with my invention, Fig. 2 is a longitudinal sectional view taken on the line 2—2 of Fig. 1, illustrating the chuck within the cylindrical barrel, Fig. 3 is a similar view, illustrating the means of securing the chuck to the con-

trolling lever, and Fig. 4 is a detail front elevation of the chuck removed from the barrel.

Referring in detail to the drawing, the numeral 1 indicates a cylindrical barrel, 60 having formed on its lower end a handle 2, which is provided with a cut away portion 3, forming a guard extension 4, for engaging a guide on an air brake device or electrical controller. The barrel 1 is provided with a central bore 5 which tapers downwardly from a point intermediate the ends thereof and is provided with one of its walls curved as illustrated at 6 to conform to the stem of an air brake valve or controller stem 7. The central bore 5 is enlarged from a point intermediate the ends of the barrel to the upper end thereof to form an enlarged bore 8. The barrel 1 is provided with an elongated slot 9 which is 75 in communication with the enlarged bore 8 thereof. A releasing lever 10 extends through the elongated slot 9 and within the barrel and has pivoted thereto a chuck 11, which will be hereinafter more fully described. A pair of oppositely disposed ears 12 are formed on a cap 13 and provided with apertures to receive bolts 14 which are adapted to extend through ears 15 formed on the barrel 1 for detachably securing the 80 cap 13 to the barrel. A coil spring 16 is mounted within the enlarged bore 8 and bears upon the releasing lever and the cap 13, to urge the chuck 11 downwardly within the tapering bore 5 of the barrel 1. 90

The chuck 11 consists of side members 17 and a rear member 18, the rear member being formed on the side members 17 at the upper end thereof as illustrated at 19. The members 17 and 18 are substantially wedge-shaped to form a wedging action between the stem 7 and the barrel 1. Formed on the upper ends of the guide members 17 are a pair of inwardly bent ears 20 which are provided with alining apertures to receive 100 a bolt 21 which passes through the releasing lever 10 for pivotally securing the chuck 11 to the releasing lever 10.

A felt washer 22 is positioned within the enlarged bore 8 of the barrel 1 and is provided with a slot to allow the lever 10 to pass therethrough, to prevent dust and other foreign matter from entering the bore 8 through the slot 9. The enlarged bore 8 may be filled with grease or other lubri- 110

cant by removing the cap 13, which will efficiently lubricate the operation of the chuck 11 within the barrel 1.

In operation, when desiring to adapt this device to the stem 7 of the air valve or electric controller, the releasing lever 10 is pushed downwardly in the direction of the handle 2, pulling upwardly the chuck 11 and the barrel 1 is placed upon the stem 7. The releasing lever 10 is then released and the spring 16 forces the chuck 11 downwardly within the tapering bore 5 between the inner walls of the barrel 1 and the stem 7, efficiently locking the barrel 1 upon the stem 7 and prevent the device from becoming accidentally detached from the stem 7 when in operation. The chuck 11 being constructed of wedge shaped members 17 and 18 will form a tight connection between the barrel 1 and the stem 7 and will take up all wear which may occur within the barrel 1 from constant usage and assure a tight connection between the barrel 1 and the stem 7 at all times. In the controlling handles now upon the market, the barrels become worn and do not fit tightly upon the stem of the electric controller or air brake valve and will rotate upon the stem 7 slightly before the stem 7 is turned to open the valve or close the circuit within a controller and in cutting off the controller or air valve, it is sometimes impossible to make the handle rotate the stem 7 sufficiently to close the valve or break the circuit within an electric controller, owing to the space between the barrel and the stem.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A device of the character described comprising a cylindrical barrel provided with a tapering bore, a handle formed on said barrel, a pair of wedge-shaped members slidably mounted within the tapering bore of the barrel, a wedge-shaped member formed on the rear edges and adjacent the upper end of the pair of wedge-shaped members, a pair of inwardly extending ears formed on the upper ends of the pair of wedge-shaped members, a releasing lever pivoted to said barrel and extending therein, a bolt extending through the ears and the lever to pivotally

secure the wedge-shaped members to the lever, and a spring mounted within the barrel for urging the wedge-shaped members downwardly within the tapering bore of the barrel.

2. A device of the character set forth comprising a barrel having a tapering bore in its lower end terminating into an enlarged bore in its upper end thereof, said enlarged bore opening out through the upper end of the barrel to receive lubricant, a cap detachably secured to the upper end of the barrel, a chuck slideable within the tapering bore, ears formed on said chuck, said barrel having a slot extending from its upper end and terminating adjacent the tapering bore, a lever extending through the slot and pivoted to said ears for raising the chuck, and a spring interposed between the chuck and lever for urging the chuck downwardly.

3. A device of the character set forth comprising a barrel having a tapering bore in its lower end and terminating into an enlarged bore in its upper end thereof, said enlarged bore opening out through the upper end of the barrel to receive lubricant, a cap detachably secured to the upper end of the barrel, said barrel having a slot extending from its upper end to a point adjacent the tapering bore, a chuck mounted in the tapering bore, ears formed on said chuck, a lever extending through the slot and resting upon the lower wall and pivoted to said ears for raising the chuck, a spring for urging the chuck downwardly, and a flexible washer mounted in the enlarged bore and having a slot to receive the lever for closing the slot in the barrel.

4. A device of the character set forth comprising a barrel, having a tapering bore, a chuck mounted in said bore and consisting of wedge-shaped side members, a rear wedge-shaped member formed on the side members and having a pair of relatively spaced slots terminating adjacent the upper end thereof to add flexibility thereto, a pair of ears formed on the upper ends of the side members and bent inwardly and upwardly, a lever pivoted to said ears between the inwardly and upwardly bent ends, and a spring for urging the chuck downwardly in the bore.

In testimony whereof I affix my signature in presence of two witnesses.

GEORGE J. SWEETSER.
